ELI N. MOYER, OF TORONTO, ONTARIO, CANADA, ASSIGNOR TO E. N. MOYER COMPANY, LIMITED, OF TORONTO, ONTARIO, CANADA.

SCHOOL DESK AND SEAT.

1,319,236.

Specification of Letters Patent.

Patented Oct. 21, 1919.

Application filed May 21, 1918. Serial No. 235,790.

To all whom it may concern:

Be it known that I, ELI N. MOYER, of the city of Toronto, in the county of York, Province of Ontario, Canada, have invented 5 certain new and useful Improvements in School Desks and Seats, of which the following is a specification.

This invention relates to school seat and desk combined units which are not fixed to 10 the floor so that they may be easily re-arranged or removed to suit the convenience of a class, or when a school room is used for social purposes, such as shown and described in my United States Letters Patent 15 No. 1246981 dated Nov. 20, 1917, and my object in the present invention is to provide a seat and desk unit which will possess all the advantages of the subject matter of my previous invention, and which will also be 20 more perfectly adjustable to the requirements of the individual child, which is better constructed mechanically, and which is readily knocked down for shipment.

I attain my object by means of the constructions hereinafter more specifically described and as illustrated in the accompanying drawings in which—

Figure 1 is a side elevation showing the desk unit and chair unit connected to a base;

30 Fig. 2 a rear elevation of the chair;

Fig. 3 a plan view of part of the base; and

Fig. 4 a vertical section on an enlarged scale, partly broken away, of one side of the desk and base.

35 In the drawings like numerals of reference indicate corresponding parts in the different figures.

The equipment includes a desk unit, a chair unit, and a base unit, to which the 40 desk and chair are removably and adjustably connected.

The base is formed of side members 1 suitably connected by cross braces 2. The chair is provided with legs 3 and the desk 45 with legs 4. The legs of both the chair and desk are provided with U-shaped leg extensions 5 which embrace the legs and are secured thereto by means of bolts 6, which pass through slots in the leg extensions and

holes in the legs. This arrangement provides means for vertically adjusting the chair or desk. 50

To each leg extension is welded a foot 7 of U-section adapted to embrace one of the side members 1 of the base, see particularly 55 Figs. 2 and 4. In each foot is formed a slot. A bolt 8 passes through a hole in the base and the slot in the foot and is provided with a head 9 which will pass through the slot when in a given direction, but will not 60 pass through the slot when turned at an angle to said position. Preferably the head is of a simple T-form. When all the bolts are turned to the proper position, the chair or desk may be removed from the base, or 65 adjusted to or from one another. The nuts of the bolts are at the under side of the side members of the base and each nut is enclosed by a cap 10 detachably secured to the under side of the base and preferably 70 formed as a glider to facilitate the movement of the base on the floor. The nuts being held from turning, the bolts may be set up as tightly as may be desired by turning the heads 9. 75

The legs of the chair are secured to the seat 11 and side rails 12 by means of the tie bolts 13 extending from back to front. By disconnecting these bolts the chair may be knocked down for shipment. The seat, 80 it will be noticed, is curved only in a direction from the front to the back, not cross-wise, and thus meets modern requirements. The rear legs are extended upward to form the side members of the back and incline 85 slightly toward the rear. The back bars 14 are substantially straight from end to end, this feature meeting modern requirements. Two back bars are employed and each is vertically adjustable so that they may be 90 perfectly adapted to the back of the pupil using the seat.

The preferable construction for adjustment is shown particularly in Figs. 1 and 2 of the drawings. Each side member of the 95 back has a vertical recess 15 formed therein in which the ends of the back bars lie. A cap member 16 is provided for each recess

secured at its ends to the side members. A clamping bolt 17 extends through each cap member and the side member of the back behind it and is adapted to be set up to 5 draw the cap against the ends of the back bars and thus securely clamp them in place. Adjustment of the back bars is thus readily effected.

A drawer 18 is fitted to slide between the 10 side rails 12 and the seat 11. The legs 4 of the desk have pairs of plates 19 secured at their upper ends. A cross bar 20 closes the space between each pair of plates at 15 their under side and a cap member 21 fitting over the tops of the legs closes the space between the plates at their upper edges.

Each pair of plates has a hole 22 formed therein and an arc-shaped slot 23 concentric with the hole. A U-shaped pin 24 is 20 provided adapted to pass through the hole and the arc-shaped slot. Other holes 25 are provided in which pins 26 are supported so that they may be projected through the outer side of each outer plate for a purpose 25 which will hereinafter appear.

27 is the desk top, preferably provided with a ledge 28 and a pencil groove 29. This top has a pair of bent metal slides secured to its under side. Each slide has 30 an upwardly extending lip 31 which engages with the downwardly directed lip 32 formed at the upper edge of a bracket 33. The lips 31 and 32 make a close fit so that while the top is frictionally held from accidental displacement, the desk top is readily moved backward and forward on the brackets. Each bracket is formed with a depending arm 34 provided with a pair of holes through which the pin 24 passes. The 35 desk top may thus be either tilted forward to enable the pupil to stand up between his desk and chair, or may be held in horizontal position or slightly tilted from the horizontal position rearwardly by projecting certain of the pins 26 to engage the rear 40 sides of the arms 34. In the drawing, the desk top is shown held in horizontal position. By projecting one of the other pins 26, the desk top may be inclined more or less from the horizontal toward the chair 45 as may be desired.

Sometimes it is desirable to lock the top either in a horizontal or in a slightly inclined position. I therefore provide at each 50 side of the desk a pin 37 which is adapted to be projected into a hole 38. The top will then be locked in a horizontal position. I also provide a sliding pin 39 at each side which may be projected to lie behind the 55 depending arm 34 when the latter is in engagement with one of the pins 26 to prevent the desk being tilted up. Only the pin 37 is shown in detail in Fig. 4, but all the pins 26 and 39 are similarly arranged, each pin

having a head to prevent it being pushed 65 out too far and being provided with a cotter pin 40 to prevent its being slipped back too far.

A bracket 35 is secured to the right hand cross bar 20 and is adapted to support an ink 70 well 36.

From the construction described it will be seen that the desk and seat may be used independently or as a double unit connected to the base. The desk and seat may be 75 adjusted to or from one another, and, with a given distance between the foot of the seat and the legs of the desk, the desk top may be adjusted to any suitable position relative to the front edge of the seat, which 80 is a very important matter to prevent children becoming stooped or round shouldered. The height of the desk top and the chair seat may be adjusted independently as may be necessary. The desk top may be 85 used either level or slightly sloping. The top of the desk swings forward out of the way, thus enabling the pupil to stand up between the desk and the chair whenever necessary. The chair is also readily disconnected and turned around with its back to the desk, which enables the chairs to be used for seating accommodation around the walls of a room with a minimum incumbrance of 90 the floor space.

If a drawing table is desired, the desk unit may be reversed in position and the desk top tilted toward the chair to the maximum limit provided by the arc-shaped slots 23.

What I claim as my invention is:

1. In school furniture, the combination of a base; a desk unit; a chair unit, one of said units being adjustable on the base to and from the other; desk top supporting brackets provided with depending arms 105 pivoted on the desk unit; and a desk top slidably mounted on said brackets, whereby the desk top may be swung to different angles to the horizontal and also slid to or from the chair unit.

2. In school furniture, the combination of a base provided with parallel side members; a furniture unit having longitudinally slotted feet of U-section fitting on the side members of the base to slide thereon; bolts 115 passing through said slots and through holes in the base members; nuts on said bolts set up at the under side of the base; and detachable caps secured to the under side of the base members adapted to prevent the nuts 120 turning, said bolts having heads which will pass through the slots when turned in one position but not in other positions.

3. In school furniture, a chair having the side members of its back vertically recessed; 125 back bars having their ends vertically movable in said recesses; a cap member for each recess secured at its ends to the side mem-

ber; and a clamping bolt for each cap member extending through the cap member and the corresponding side member between the back bars.

5 4. In school furniture, a furniture member provided with legs; U-shaped leg extensions each embracing a leg and each provided with two longitudinal slots; bolts

passing through the slots and the legs; feet of U-section welded to the lower ends 10 of the leg extension; and a base having parallel side members on which said feet are adapted to slide.

Signed at Toronto, Canada, this 15th day of May, 1918.

ELI N. MOYER.
